H. K. SMITH

CLASP

Original Filed Dec. 16, 1922.

Patented June 15, 1926.

1,588,630

UNITED STATES PATENT OFFICE.

HERBERT KEMP SMITH, OF NEW ORLEANS, LOUISIANA, ASSIGNOR TO MERLE POWE SMITH, OF NEW ORLEANS, LOUISIANA.

CLASP.

Application filed December 18, 1922, Serial No. 607,381. Renewed November 3, 1925.

This invention relates to clasps adapted to be used in connection with watch fobs or as a fastening means for the end of key chains.

5 An object of the invention is the provision of a simple and efficient clasp which will grip a part of the clothing and be locked in such a reliable manner that the clasp will be safe against accidental or unauthorized removal.

Other objects and advantages of the invention will become apparent during the course of the following description.

The invention is illustrated by way of 15 example in the accompanying drawings, in which,

Figure 1 is a view in perspective of the clasp attached to a trouser band and used in connection with a watch fob.

20 Figure 2 is an end view of the same.

Figure 3 is a vertical sectional view of the clasp shown in Figure 1.

Figure 4 is a view in perspective of a 25 modified form of the clasp adapted to be used in connection with a key chain.

Figure 5 is a vertical section of the same.

Figure 6 is a view in perspective of the clasp shown in Figures 1 to 3, in open position.

30 Referring to the drawings, 1 designates a front plate which may be engraved in any suitable manner in order to display the owner's monogram or some design of a fraternal or secret society to which the

35 owner may belong. Where desired, instead of the engraving, the design or monogram may be cut in the face of the plate. The materials employed may be of any type of metal suitable for the purpose. The front

40 plate is provided with a slot 2 at its lower end through which is threaded a fob 3. An ear 4 projecting from a lower corner of the front plate 1 is perforated to receive a chain 5 which carries a watch located in a

45 pocket 6 of the trousers.

The front plate is bent rearwardly as shown at 7 and provided with a returned bent portion 8. Projecting downwardly, and offset from the returned bent portion 8, 50 is an integrally formed spring tongue 9 spaced from the front plate 1. The tongue 9 has considerably less width than the returned bent portion 8. The returned bent portion is provided upon opposite sides of the tongue 9 with bearings 10. A pin 11 is

integrally formed on each of a pair of legs 13 and 14 of a clamping member 15.

The tongue 9 projects between the legs of the clamping member and engages a plate 16 pivotally mounted at 17 on the outer 60 face of said clamping member, with the upper free end 18 of said plate projecting upwardly and over the space between the legs 13 and 14 of said clamping member and forced inwardly by the spring tongue 9. 65 The tongue 9 has sufficient resilience and rigidity to maintain the jaw 19, formed on the lower end of the clamping member, projected into the slot 2.

The clamping member is provided with 70 an inwardly projecting resilient tongue 20 engaging the slot 20^a formed by punching out a portion of the metal of the locking plate 16 to provide the finger piece 26. The engagement of the end of the tongue with 75 in the slot 20^a prevents movement of the locking plate 16 on its pivot 17 when the jaw 19 of the clamping member forces the trouser band into the slot 2 of the front plate 1. 80

It will be noted that the clasp is adapted to engage either the trouser band 21 or a belt when locked in position to prevent loss of a watch. The clasp shown in Figures 1 to 3 inclusive is locked upon a trouser 85 band and if it be desired to remove the clasp it is only necessary to exert pressure on the finger piece 26 whereby the resilient tongue will be forced inwardly and away from the locking member 16 to permit the locking member to be oscillated and released from beneath the spring tongue 9.

As shown in Figure 6 the release of the locking member 16 from the spring tongue 9 and the end of the tongue 20 from the 95 slot 20^a of the plate 16 will permit rocking of the clamping member 15 and thereby release the jaw 19 from its position where it has forced the trouser band into the elongated slot 2 in the plate 1. 100

The clasp may be applied to a belt or trouser band by locating the plate 1 at the rear of the part of clothing to which the same is to be applied when the pivoted clamping jaw 15 may be swung toward the 105 plate 1 with the jaw 19 forcing the clothing into the slot 2. The locking plate 16 is swung on its pivot 17 until the upper free end 18 of said locking member is forced beneath the spring tongue 9 as the locking 110

plate 16 forces the spring tongue 20 inwardly toward the plate 1. The cooperating spring tongues 9 and 20 maintain the locking plate 16 against accidental removal. The free end 16 of the tongue engages the inner face of the finger piece 26 and projects slightly into the slot 20^a of the locking plate 16 whereby the said plate is locked against oscillation.

Figures 4 and 5 disclose a modification of 10 the clasp. This form of clasp is provided with a front plate 1 adapted to be engraved or decorated in a manner similar to the front plate of the clasp shown in Figure 1. A resilient tongue 9^a and a clamping member 15^a 15 are provided, with the clamping member pivotally mounted on the returned bent portion 8 of the plate 1. The toothed jaw 19 of the clamp projects within the slot 2 of the front plate and is adapted to pinch or force 20 the part of the clothing so engaged, into said slot.

A tongue 20 is provided at the rear of the clamping member 15^a to engage the notch 20^a of the locking plate 16^a and adjacent the finger piece 26 which projects beyond the plane of the tongue 9^a. The end of the tongue or spring member 9^a is bevelled as shown at 22 and adapted to engage the complementary bevelled portion 23 of the plate 16^a which is pivotally connected at 17 to the clamping member 15^a. The spring tongue 9^a engaged with the locking plate 16^a through the bevelled portion of the respective members, tends to force the locking plate 16^a inwardly while the tongue 20 presses outwardly against the locking plate whereby the locking plate is rigidly held in place to prevent accidental movement of the clamping member 15^a on its pivot pin 11^a. The legs 13 and 14 of the clamping member 15^a 40 are provided with journals 27 which are mounted on the pins 11. The pin 11^a is rigidly secured to the back of the resilient tongue 9^a.

45 At the extreme end and centrally of the lower edge of the plate 1 is formed an ear 24 provided with a perforation 25 which is adapted to receive one end of a chain which is provided with a key ring at its other end.

50 The operation of the modified form of clasp shown in Figures 4 and 5 is as follows:

Pressure upon the finger piece 26 moves the resilient tongue 20 inwardly while the bevelled edge of the locking plate 16^a is moved sufficiently away from the bevelled end of the tongue 9^a to permit the locking plate to be swung on its pivot 17 and moved out of engagement with the end of the tongue 9^a. The clamping member 15^a is now free 60 to be moved on its pivot and to be swung outwardly away from the plate 1 to release the clasp from the trouser band or from a belt.

65 It must be borne in mind that the clasp is adapted to be suitably attached to either the band of a pair of trousers or a belt and

in either case the clasp is locked against accidental or unauthorized release from the part of the clothing to which it has been attached.

When either form of clasp is employed in 70 combination with a belt, the toothed jaw 19 of the clasp projects into the slot 2 and the belt is inserted and slideable in the space between the pivoted clamping member 15 and the front plate 1 as shown more particularly 75 in dotted lines in Figure 4.

What I claim is:

1. A clasp comprising a front plate provided with a returned bent portion spaced from the upper end of said plate and a 80 transverse slot at its lower end, a clamping member having legs pivotally mounted on the returned bent portion, a resilient tongue projecting from the returned bent portion between the legs of the clamping member, a locking plate pivotally mounted on the clamping member and having its free end 85 engaged by the free end of the resilient tongue, a jaw on the lower end of the clamping member adapted to be maintained within the slot of the front plate by the action of the resilient tongue on the clamping member, the locking plate being provided with a notch, and a tongue on the clamping member 90 engaging the notch in the locking plate 95 to prevent disengagement of the locking plate from the resilient tongue to prevent accidental or unauthorized removal of the clasp.

2. A clasp comprising a front plate having 100 an integrally formed spring member spaced from the front plate and a slot located adjacent its lower end, a clamping member pivotally mounted on the rear face of and at one end of the front plate, and provided 105 with a jaw adapted to be maintained in the slot and means pivoted on the jaw and engageable with the spring for causing the spring to maintain the jaw in an operative position within the slot.

3. A clasp comprising a front plate having 110 an integrally formed spring member spaced from the front plate and a slot located adjacent its lower end, a clamping member pivotally mounted on the rear face 115 of the front plate, and provided with a jaw adapted to be maintained in the slot, and means cooperating with the jaw and spring for causing said spring to maintain the jaw 120 in position in the slot, and means for locking the clamping member against accidental movement.

4. A clasp comprising a front plate having 125 an integrally formed spring member spaced from the front plate and a slot located adjacent its lower end, a clamping member pivotally mounted on the rear face of the front plate, and provided with a jaw adapted to project into the slot, locking means pivotally mounted on the clamping 130

member engageable with the spring member for maintaining the jaw projected into the slot, said clamping member having a portion bent inwardly towards the locking means 5 and engageable with said means to prevent accidental movement of the locking means.

5. A clasp comprising a front plate having a tongue integrally formed with said plate spaced from the rear face of the front 10 plate, a clamping member provided with legs pivotally connected on opposite sides of the tongue where the tongue is integrally connected with the front plate, said tongue being offset from the plane of the clamping 15 member, a jaw provided on the lower end of the clamping member adapted to engage a piece of clothing and pinch the same against the rear face of the front plate, a plate pivotally mounted on the clamping 20 member and engaged by the free end of the tongue, said plate provided with a notch at its free end, a tongue projecting from the clamping member adapted to project into the notch in the plate for locking the plate 25 against movement to maintain the jaw in engagement with the clothing, and a finger piece projecting outwardly from the plate adjacent the notch and adapted, when depressed, to release the plate from the second 30 mentioned tongue.

6. A clasp comprising a front plate having an integrally formed spring member

spaced from the front plate and a slot located adjacent its lower end, a clamping member having legs pivotally mounted on 35 the rear face of the front plate and provided with a jaw adapted to project into the slot, said springs projecting between the legs of the clamping member and means for locking the spring in operative relation with the 40 clamping member.

7. A clasp comprising a front plate having an integrally formed spring member spaced from the front plate and a slot located adjacent its lower end, a clamping member pivotally mounted on the rear face of the front plate and provided with a jaw adapted to project into the slot, means engageable with the spring for causing said spring to maintain the jaw in the slot, and means for locking the spring engaging means in operative 45 relation with the spring.

8. A clasp comprising a front plate, a clamping member mounted in bearings spaced from the front plate, a spring projecting from the front plate, and movable through the clamping member, means cooperating with the clamping member and the spring and adapted to lock the spring and clamping member together for causing the 55 spring to maintain the clamping member in operative relation with the front plate.

HERBERT KEMP SMITH.
